United States Patent Office

Des. 222,575
Patented Nov. 9, 1971

222,575

TOOL FOR UNLOCKING AUTOMOBILE DOORS

George L. Steck, Dayton, Ohio, assignor to Steck
Manufacturing Company, Inc., Dayton, Ohio

Filed Nov. 12, 1970, Ser. No. 25,926

Term of patent 14 years

Int. Cl. D8—05

U.S. Cl. D8—16

FIG. 1 is a perspective view of the tool for unlocking automobile doors.

FIG. 2 is a bottom plan view of the tool.

FIG. 3 is a side elevational view of the tool.

FIG. 4 is an end elevational view of the tool as viewed from the left side of FIG. 3.

FIG. 5 is an end elevational view of the tool as viewed from the right side of FIG. 3.

I claim:

The ornamental design for a tool for unlocking automobile doors, as shown and described.
